Inventor

JOHN W. ATWOOD,
By his Attorney
Frank W. Allen.

UNITED STATES PATENT OFFICE.

JOHN W. ATWOOD, OF WAUREGAN, CONNECTICUT.

FASTENER FOR MEETING-RAILS OF SASHES.

SPECIFICATION forming part of Letters Patent No. 400,535, dated April 2, 1889.

Application filed December 14, 1888. Serial No. 293,636. (No model.)

To all whom it may concern:

Be it known that I, JOHN W. ATWOOD, a citizen of the United States, and a resident of Wauregan, in the county of Windham and State of Connecticut, have invented certain new and useful Improvements in Fasteners for the Meeting-Rails of Sashes, which improvements are fully set forth and described in the following specification, reference being had to the accompanying sheet of drawings.

This invention is in sash-fasteners, and has particular relation to that sub-class used commonly for locking together the meeting-rails of window-sash, in which a pivoted arm is attached to the rail of one sash and is adapted to swing into proper position to interlock with a suitable plate on the rail of the adjacent sash.

In this class of devices much trouble and annoyance have resulted from loosely-fitted or badly-worn fasteners, which not only allow the windows to rattle, but permit the entrance of drafts of air. When such fasteners become worn, or for other reasons loose, it becomes necessary to adjust one of the plates relative to the other to cause the lock to bring the sashes into close engagement. As the adjustment required in such cases is generally less than the width of the screw-holes, it becomes necessary to plug up said holes and make new ones, thus disfiguring the sash.

My present invention has for its immediate object the improvement of such fasteners, to the end that any desired adjustment may be quickly made within the locking device, rather than by the removal of its supporting plates, as before described.

To illustrate my invention, I have annexed hereto a sheet of drawings, in which—

Figure 1 is a perspective view of a sash-fastener embodying my improvement. Fig. 2 is a detached face view of the disk *o*. In Fig. 3 a modification of my invention is shown, in which one check-nut is dispensed with.

Referring to the drawings, the letter *a* denotes a plate secured to the rail *A* of one sash, and *b* a similar plate on the adjacent sash *B*. Plate *a* has pivoted to its upper side an arm, *c*, whose free end may be swung in a horizontal plane to engage a spring-pressed cam, *d*, hung in plate *b*.

My device may be readily applied to any of the sash-fasteners of this class; but I have

chosen the one illustrated in Fig. 1, and which I have just briefly described, as it is a well-known type of said class.

Heretofore, so far as I am familiar with such fasteners, the free end of said arm *c* has been formed with a downwardly-projecting fixed lug that interlocked with the cam *d*; but in the improved form here shown I have provided a lug on said arm *c* that may be adjusted relative to the pivotal center of said arm. My preferred form of construction is shown in Fig. 1, in which the outer end of arm *c* is substantially square in cross-section, and is screw-threaded at the corners or angles to receive nuts *n* *n'*, whose perimeters are milled or checked, as shown. Between these nuts is a disk or washer, *o*, having a square opening to fit the squared stem of arm *c*, and having a downwardly-projecting lug, *o'*, adapted to engage the cam *d* when swung at right angles to the sash. This lug *o'* may be quickly moved outward or inward on arm *c*, and securely fixed in any desired position by correspondingly adjusting the nuts *n* *n'*.

In the modification illustrated in Fig. 3 the nut *n* is dispensed with and the disk *o* is provided with a screw-threaded round hole that fits the threaded stem of arm *c*. Said disk then serves as one nut, and the nut *n'* as a check-nut to retain it in position after adjustment.

With this construction the disk may be adjusted on the arm *c* by rotating said disk one or more revolutions, the degree or minimum limit of adjustment being governed by the fineness of the screw-thread.

My described improvement adds but little to the cost of this class of devices, yet it practically and effectually overcomes the objection heretofore existing.

Having thus described my invention, I claim—

In combination with a cam or similar projection on one sash, a lever-arm bearing an angular projection adjustable on said lever-arm, and adapted to swing into engagement with said cam, as set forth, and a check-nut on said lever-arm for retaining said angular projection in a given position, all substantially as and for the object specified.

JOHN W. ATWOOD.
